DISPLAY BINDER

Elmer W. Ericson, Chicago, Ill., assignor to The Barrett Bindery Co., Chicago, Ill., a corporation of Illinois

Application November 28, 1938, Serial No. 242,704

18 Claims. (Cl. 281—33)

This invention relates generally to display binders and more particularly to binders of the type used by salesmen and others for displaying in a neat and attractive manner pictures, data, and other matter forming a part of the presentation.

The object and general nature of this invention is the provision of new and improved means for displaying one sheet above the other so as to provide what is called a double page spread, that is, the picture or other presentation is of such size as to require two sheets for its display. In this connection it is a feature of this invention to provide a display binder of the type that can be folded into a compact book form but which may be extended for display purposes to hold one set of sheets above the other but in substantially coplanar relation, thus making it possible to display relatively large charts, pictures, maps, and other subject matter without requiring a binder of excessively large size.

A further feature of this invention is the provision of a display binder having a folding easel associated with the front and back covers so that the binder may be folded into compact book form to facilitate carrying the same and may be erected for display merely by turning back the front cover and unfolding the easel, thereby setting up the binder so that the front cover and easel support the sheets in extended relation one above the other, the binder being conveniently and quickly folded back to its compact book form merely by closing the front and rear covers over the sheets, this action automatically folding up the easel.

More specifically, a feature of this invention is the provision of a cover carrying mechanical wire bound or ring or arch-connected sheets so that the latter are protected from wear when not set up for display, in connection with means cooperating with the cover and reacting against the sheet binding means for quickly and conveniently setting up the sheets, one sheet above the other, for visual presentation and demonstrating purposes.

Another feature of this invention is the provision of a binder having sheet binding means of the mechanical type in which the joint or connection from which the individual sheet-holding rings extend is disposed in a concealed position between two panels of the binder so as not to interfere with the leaves, no matter to what position the binder is turned.

These and other objects and advantages of the present invention will be apparent to those

skilled in the art after a consideration of the following detailed description taken in conjunction with the accompanying drawings.

In the drawings:

Figure 1 is a perspective view of a display binder embodying the principles of the present invention and shown as arranged for display;

Figure 2 is a view showing the binder folded into compact book form;

Figure 3 is an enlarged section taken along 10 the line 3—3 of Figure 2;

Figure 4 is an enlarged fragmentary section taken vertically through the central portion of the display binder shown in Figure 1;

Figure 5 shows the form of mechanical binding 15 which may be employed in the binder of Figures 1 to 4;

Figure 6 shows a modified form of binder arranged for display and employing sheet binding means of the type known as loose leaf metal, that is, embodying rings, arches or the like that can 20 be opened readily at any time to insert or remove a sheet;

Figure 7 is a fragmentary section showing the binder of Figure 6 closed;

Figure 8 shows a modified form of the present invention which is similar to that shown in Figures 6 and 7, but in which a loose-leaf metal having rings is employed, instead of hinged arches specifically shown in Figure 6;

Figure 9 is a fragmentary section taken along 25 the line 9—9 of Figure 8;

Figure 10 is a view similar to Figures 6 and 8, showing a third form of this invention which embodies certain improvements in the arrangement of the easel panels and the sheet binding means;

Figure 11 is a fragmentary view illustrating the type of sheet binding means employed in the construction shown in Figure 10;

Figures 12, 13, 14, and 15 are sections showing the manner of assembling the binder; and

Figure 16 is a fragmentary view of the rigid reenforcing sheet employed in the binder shown in Figures 10 to 15, inclusive.

Referring now to the drawings, the form of the display binder embodying the principles of the present invention as shown in Figures 1 to 4 comprises a cover indicated in its entirety by the reference numeral 1, an easel section 2, suitable sheet binding means 3, and a set of superimposed separate sheets 4 having perforations 5 (Figure 1) punched therein along the inner edges.

The cover 1 consists of a front cover member 7 and a back cover member 8, each of which in-

45

50

55

- cludes a rigid board 9 bound, as at 10, in cloth, imitation leather, or other material, as desired. The cover binding 10 preferably is continuous and extends from one cover member to the other.
- 5 Generally centrally thereof the cover members 7 and 8 are spaced apart and the material 10 arranged to form a flexible portion indicated at 11. This flexible portion serves as a hinge and permits the covers to be folded together, as in Figures 2 and 3, or turned back one on the other, as indicated in Figure 1. Also, the flexible section 11 is of sufficient extent to embrace and enclose the sheet binding means 3. The front cover 7 also includes a relatively heavy sheet 15 of fiber board or other material glued to the inner side of the board 9, as best indicated in Figure 3. Preferably, the sheet 15 overlaps the edge portions of the fabric or other material 10, as indicated at 16, which is the usual practice.
- 10 The easel 2 comprises two panels 19 and 20 and a foldable connecting panel section 21, as best indicated in Figures 1 and 3. The sections 19, 20, and 21 are connected together to form a sheet or strip which is folded at the points 22, 23, and 24, the inner panel 19 being appreciably heavier than the outer panel 20 since the panel 19 is required to support a certain portion of the weight of the cover and the sheets 4, as will be described below. The folded section or stub 23 (Figures 1 and 3) of the easel 2 is permanently secured, as by rivets 26 or the like, to the outer edge of the back cover 8 so that when the latter is swung away from the panel 19, the easel 2 is extended, as indicated in Figure 1, and the sheets 4 are supported by the panel 19. Thus, broadly considered, the parts 7 and 19 form rigid backs for the binder or book and the part 8 serves as a strut to hold the parts 7 and 19 in extended relation.
- 15 The connecting panel 21 preferably is creased or scored at the fold line 24 in such manner that when closing the binder the two parts of the section 21 tend in and of themselves to fold inwardly without requiring that they be moved manually. Thus, when extended for display purposes, as in Figure 1, by simply lifting the device by the cover 7, or by turning the cover 7 down over the lower sheets 4 or the part 19 and then grasping the covers 7 and 8, the parts 8, 19, 20, and 21 fold together as shown in Figure 3.
- 20 The sheet binding means, indicated in its entirety by the reference numeral 3, may be of any suitable character, but preferably it is constructed so that the sheets 4 may be turned freely one at a time from one side of the binder to the other. For example, the binding means 3 may be one of the mechanical or wire bound types known in the industry as "Spiral," "Wire-O," "Cercla," "Coil," etc., and by way of illustration only I have shown the sheets 4 as carried by binding of the "Wire-O" type, best shown in Figures 4 and 5, which is in the form of a wire 33 having ring-like arches or loops 34, each of which consists of a pair of generally arcuate sections 35 and 36 connected by a short rounded end loop 37, the adjacent sections 35 and 36, respectively, of contiguous arches 34 being connected by a longer loop 38, the loops 38 thus serving as means connecting the adjacent ends of the arches 34 while the ends 37 are free and, in assembly, are pressed into the perforations 5 to connect the sheets 4 in assembled relation. The connecting sections 38 in this form are arranged to lie between the panels 19 and 20 when the binder is

extended, as best shown in Figure 4, since these parts separate when the binder is closed, as shown in Figure 3, but the sections 38 may be otherwise disposed if desired or required. The panels 15, 19, and 20 are also punched to receive the binding parts 34, this being most conveniently done when the latter are inserted in the sheets 4 and before the panel 15 is glued to the front cover 7 and before the stub 23 is riveted to the outer edge of the back cover 8. In fastening the panel 15 to the inside of the front cover the panel 15 is secured in place to make available the maximum amount of the parts 34 to receive the sheets 4, as best shown in Figure 4.

While I have described a particular kind of binding means for the sheets 4, it is to be understood that this is for illustration only and that this invention is not necessarily limited to any particular binding means, as will appear from the description below of other forms of this invention. It will also be understood that where economies are desirable, the sheets and panels may consist of or be formed from any suitable grade of board or paper stock, as desired. Figures 8 and 10, described below, show two of such forms.

The operation of the display binder described above is substantially as follows:

The salesman or other user ordinarily carries the binder about in the position shown in Figure 2, namely, folded into compact book form. When it is desired to set up the binder for display, the user merely swings the front cover 7 back until it rests against the inner edge of the back cover 8, at the point indicated by the reference numeral 32 in Figures 1 and 4, this movement being accommodated by the flexible cover section 11. The front panel 19 is then moved forward to set up the easel 2, which extends the section 21, and the parts take the position shown in Figure 1, the upper cover 7 and the panel 19 thus serving as backs for the leaves 4. In practice, the opening of the binder for display purposes can be made with one movement. The opening movement of the front cover 7 causes the latter to move relative to the arches 34 to a position substantially underneath them, as indicated in Figure 4, and closely adjacent to the inner edges of the easel panels 19 and 20. The connecting section 21 of the easel limits the outward or spreading movement of the panels 19 and 20, and the panel 20 serves as a tension member reacting against the part of the binding means 3 against which the inner edge of the upper cover member 7 bears to determine the angle at which the parts are supported. The connecting panel 21 is so designed that when the front cover 7 rests against the upper edge of the back cover 8 and the easel 2 is extended, the cover 7 and the heavier panel 19 of the easel 2 are supported in substantially coplanar relation, as indicated in Figure 4, where- 60 by the sheets 4 are supported one above the other in edge to edge relation and also substantially in the same plane. The weight of the upper sheets and the front cover 7 is supported by the front cover 7 resting against the inner or upper edge of the back cover 8 and reacting at its inner edge against the binding means 3 which, in turn, is held in position by the inner edges of the easel panels 19 and 20, the binding 3 bearing down on the panel 19, and hence the latter is preferably 70 a rigid member, and pulling up on the tension panel 20.

When returning the binder to its closed position (Figure 2) all that it is necessary to do is to lift the binder and the easel will automatically

fold up between the back cover and the sheets by virtue of the creasing or scoring 24 of the connecting section 21, while the covers 7 and 8 will close over the binding 3 and sheets 4, as shown in Figure 3. Thus, like the opening operation, the closing of the binder can be done with one continuous operation.

It will be noted from the above description that the sheets are supported in compact form and that the front and back covers 7 and 8 protect the sheets while the flexible connecting section 11 of the covers encloses and protects the binding 3. Yet it is the work of only a moment to open the display binder and set the same up with the sheets disposed in generally upright position to facilitate a presentation of the material printed or carried thereon. The setting up of the display binder is thus accomplished without the moving, adjusting, or snapping of any mechanical devices, the closing of the display binder being effected in the same manner. It will also be seen that when the binder is closed there is no operating mechanism or sheet binding exposed. The method of manufacturing is simple, since the two covers with their binding, which forms the flexible connecting means between the covers, are entirely separate from the folding easel, which consists of sections bound or hinged to form one continuous easel. The punching of the easel panels and the panel 15 that is glued to the cover is best effected when the sheets are punched. Thus, the final assembly of the unit requires only that the fold 23 of the easel be riveted to the back cover and the panel 15 glued to the front cover.

Mechanical binding means of the type described above produces a compact assemblage but does not as readily accommodate the exchange or replacement of single sheets as binders of the loose leaf type. Figures 6 and 7 illustrate the principles of the present invention as embodied in a loose leaf binder 44 having cover members 45 and 46 connected together by a flexible section 47 that is preferably formed by spacing apart the cover boards 49 and 50 and connecting them by the binding material 51 which may be leather, imitation leather, fabric, or any other suitable material. In the more economical forms, the parts 45, 46, and 47 may be of paper or board stock. Loose leaf metal 53, consisting of a backbone 54 and hinged arches 55 having straight sides 56 and 57, is rigidly fixed to the cover member 45 adjacent its inner edge by any suitable means, such as rivets 58.

The binder 44 includes an easel unit 62 which consists of a rigid panel 63, a tension panel 64, and a connecting panel 65 creased or scored, as at 66, to fold inwardly, as in the form of the invention described above. The panels 63, 64, and 65 are connected at fold lines 67 and 68, the latter portion forming a stub 71 which is fastened, as by rivets 72 or any other suitable means, to the outer edge of the other cover member 46. The panel 63 preferably is of heavier stock than the other panel since it is required to be sufficiently rigid to cooperate with the other parts to hold the binder in display position. The inner edges of the panels 63 and 64 are perforated to receive the arches 55 of the loose leaf metal 53, and the inner edge 64a of the panel 64 is constructed to be strong but flexible, as will be clear from Figure 6. The sheets or leaves carried by the arches 55 are indicated at 74.

The opening and closing movements of the

binder 44 are substantially the same as the binder shown in Figures 1 to 4. When the binder is closed the easel 62 folds in between the sheets 74 and the cover member 46, both easel panels 63 and 64 lying on the side of the sheets 74 opposite the base or backbone 54.

The binder is arranged for display position by opening the covers as in an ordinary binder, and then grasping the cover member 45 and lifting the binder to permit the cover member 46 to be swung back against the upper cover member 45 to support the latter and the unfolding of the easel panels 63, 64, and 65, the latter determining the angle between the easel panels. It will be noted that in this action the inner edges of the easel panels 63 and 64 move relative to the rings from the straight sides 56 of the arches (Figure 7) to the other straight sides 57. The panel 64 acts in tension against the binding rings 55 of the loose leaf metal 53, which is rigidly secured to the cover member 45, and determines the angular position the cover member 45 takes relative to the other cover member 46 when the binder is extended for display, as shown in Figure 6. As in the form of the invention shown in Figures 1 to 4, the easel panels 64 and 66 are so designed that when the binder is in display position the rigid cover member 45 and the rigid easel panel 63 are in substantially coplanar relationship. It will also be noted that in this form of the invention the sheets 74 are supported upon the straight portions of the arches 55, both when the sheets are in their lower position or in their upper position. The support of the sheets for display on the straight portions of the arches 55 is an advantage in that the sheets are maintained in the proper position at all times. When the binder is supported for display, it will be seen that the upper cover member 45, together with any sheets lying against it, bears downwardly through the loose leaf metal 53 against the rigid easel panel 63 and backwardly against the rigid cover member 46, the angular movement of the upper cover member 45 being determined by the effective length of the easel panel 64.

Mention was made above to the fact that the principles of this invention might well be embodied in an economical form of binder in which the covers are made from cardboard or the like. Referring now more particularly to Figure 8, the reference numeral 80 indicates in its entirety a binder having covers 81 and 82 formed of relatively inexpensive paper or board stock connected together by a flexible cloth section 83 glued to the covers. Loose leaf metal 85, which includes divided rings 86 hinged to a support or backbone 87, is fastened to the cover 81 by rivets connecting the backbone 87 to the edge of the cover 81 at or adjacent the portion to which the flexible section 83 is glued. The loose leaf ring metal 85 is of conventional construction and supports a plurality of sheets 89.

The easel portion 91 of the binder shown in Figures 8 and 9 includes a strip of paper stock of suitable weight having sections 93 and 94 connected to a rigid section 95, which may, if desired, be formed by an extension of the strip 93, 94 and provided with side folds 99 (Figure 9) to secure the desired rigidity. If further rigidity is desired than can be provided by the flaps 99, the sheet 95 may be reinforced by a rigid sheet of heavier stock glued thereto. The ends of the sections 93 and 95 adjacent the fold line 95a are punched to receive the rings 86, and the ends of

the sections 93 and 94 are creased, as at 93a and 94a, to form a stub 96 which is secured in any suitable manner as by gluing, or by a rivet 97, to the outer end of the cover 82. The section 94 is provided with a fold line 98 which is creased so that when the binder is closed the section automatically folds upwardly and inwardly similar to the forms shown in Figures 1 and 6. As in the forms of the invention set forth above, the tension sheet 93 acts at the point 97 and against the rings 86 to hold the upper cover 81 in a position generally in the same plane as the lower rigid sheet 95, whereby the sheets 89 can be displayed one above the other in generally coplanar relation.

A binder of this type can be manufactured very inexpensively, actually at a cost only slightly greater than the ordinary ring binder, yet, by virtue of the panels 93, 94, and 95 and their arrangement as described above, the binder may be quickly opened into display position and as quickly folded to closed position without the manipulation of any struts, snaps, hooks or other objectionable accessories.

Figure 10 illustrates a binder 100 similar to that shown in Figure 7 and just described. In Figure 10, the binder is also of inexpensive construction, embodying cardboard covers 101 and 102 connected together by a fabric section 103 that is flexible. In this form of the invention, the sheet binding means 105 is of the mechanical type, sometimes known as permanent binding inasmuch as when completed, the binding means is not separable to permit removing or replacing sheets, and is of the type known in the art as "Cercla" binding. This binding consists of a joint or connecting section 107 formed of sheet metal and provided with rings or arches 108 preferably formed integrally with the section 107. The rings or arches 108 are inserted through the punched openings in the sheets to be bound, and then the ends 109 of the parts 108 are disposed against the connecting section or joint 107. Then the portion 110 of the connecting section 107 is crimped or pressed downwardly to clamp the ends 109 and lock them in place. The connecting section or joint 107 thus connects all of the rings 108 together. It is not necessary, of course, to have all of the rings 108 of any one binder connected together, since the binding means may, for example, be divided into two or more sections, especially in the smaller binders where it is not necessary to have a set of continuous uniformly spaced binding rings or arches.

The binder 100 has a supporting easel 115 that includes interconnected panels or sheets 116, 117, and 118, the latter having an inwardly creased fold line 119, and preferably the sections 116 and 117 are connected integrally together at a fold line 121 adjacent which the sheets 116 and 117 are punched, preferably simultaneously with the sheets 122 forming the pages of the binder. A sheet 123, which is to be glued to the cover 101 as will be described below, is also punched and bound by the rings 108 at the same time as the panels 116 and 117 and the sheets 122. In the more inexpensive forms of the binder, such as the one illustrated in Figure 10, the sheets or panels 116, 117 and 118 are formed in one strip, 70 as illustrated, having their ends brought together to form a stub 124 and glued or riveted to the outer edge of the cover 102.

In this form of the invention the rigid panel section, indicated at 130 and which cooperates with the cover 102 and the other sheets 116 and

118 to complete the easel support 115, includes a sheet 131 of somewhat heavier stock, depending upon the size and weight of the binder, than the panel 117. The sheet 131 is glued to the panel 117 after the sheets 116, 117, and 123 and the leaves 122 are punched and bound by the binding means 105. The manner of mounting the rigid reenforcing panel 131 will now be described.

Referring now to Figure 12, this view shows the sheets 122, the gluing sheet 123, and the easel 10 panels 116 and 117 punched to provide apertures 135 to receive the binding means 105. The binding is then applied by inserting the rings 108 through the openings 135, and then crimping the joint 107 to fasten the rings in position. Then 15 the joint 107 is swung over to a position over the easel sheet 117, as shown in Figure 13. Next, the reenforcing panel 131, which, as best shown in Figure 16, is provided with punched openings 135a, each of which has a slot 136 leading out to 20 the adjacent edge of the sheet 131, is run through a gluing machine to apply glue to one side thereof, and then the panel 131 is applied with the glue side toward the panel 117 and firmly pressed thereagainst, the slots 136 permitting the rings 25 108 to be forced into the slots 135a at the inner edge of the sheet 131 as best shown in Figures 14 and 15. Lastly, glue is spread on the back side of the gluing panel 123 and the latter fastened to the cover 131, as indicated in Figure 14, 30 and at this time the edges forming the stub 124 of the easel are riveted or glued to the outer edge of the upper cover 102. This completes the binder, and the same may be set up in display position shown in Figure 10 or folded to a position similar to that shown in Figure 3. It will be understood that the thicknesses of the various parts are somewhat exaggerated in Figures 12 to 15 in order to illustrate the construction, and that actually the sheet 131 is glued to and lies 35 closely against and reenforces the panel 117.

One of the advantages of the construction shown in Figures 10 to 15 is that the joint 107 of the binding means 105 is, after the binder has been completed, entirely hidden from view and 45 entirely removed from any position in which any of the sheets 122 might be caught thereon. The leaves 122 turn freely at all times, whether the binder is opened as an ordinary book or set up for display, as in Figure 10, with the leaves turned 50 from one position to another to provide a double-page spread.

The feature of gluing the reenforcing panel, as at 131, to the easel panel 117 provides an arrangement which is particularly advantageous in 55 that the desired rigidity for the member 130 of the easel may be secured without varying the thickness of the stock from which the panels 115, 116, and 117 are formed, since to vary rigidity of the member 130, it is necessary only to supply 60 reenforcing sheets 131 of different thicknesses.

While I have shown and described above the preferred means in which the principles of the present invention have been embodied for the purpose of illustrating the same, it is to be understood that my invention is not to be limited to the specific details shown and described above, but that, in fact, widely different means may be employed in the practice of the broader aspects of my invention.

What I claim, therefore, and desire to secure by Letters Patent is:

1. A display binder comprising rigid front and back covers having a section connecting adjacent edges of said covers together in spaced relation, 75

- 1 a folding easel comprising a pair of panels and a spacing connector secured to said panels and to one of said covers, and binding means connecting the inner edges of said panels and the other cover so that when the latter is thrown back against the inner edge of said one cover, the inner edge of said other cover reacts against said binding means and the inner edges of said easel panels. 5
2. A display binder comprising rigid front and back covers, a section connecting the inner edges of said covers, binding means connected to the inner edge of one of said covers, and a folding triangular easel stand having two panels the inner edges of both of which are connected to said binding means while the outer edge of one is secured to the outer edge of the other of said covers, said one cover being movable to a position behind said binding means and adjacent the inner edge of said panels so that when said one cover is thrown back against the edge of the other cover, said easel supports said one cover and the other of said panels in flat coplanar relationship so as to display two sheets simultaneously. 10
3. A display binder comprising a pair of rigid cover members, a section hingedly connecting said cover members, sheet binding means connected to one of said rigid cover members and adapted to receive a plurality of sheets, a tension sheet connected to said binding means and to the other cover member, so as to determine the angle between said members when said one cover is folded back against the inner edge of the other, a substantially rigid sheet also connected to said binding, and foldable means connecting said rigid sheet to said other cover member, so as to hold said rigid panel in substantially coplanar relation with said one cover member for displaying two of said sheets simultaneously. 15
4. A display binder comprising a plurality of sheets, a panel at one side of said sheets, a folding easel at the other side comprising two panels connected to said two panels, the inner edges of said panels and said sheets being punched to form holes therein, mechanical binding disposed in said holes and receiving said sheets and panels, a pair of rigid covers having a section interconnecting the covers, one of said covers being secured to said one panel, and means securing the outer edge of the other cover to said connecting element and the outer panel of said folding easel, said easel panels and said one cover and said one panel being movable to a point adjacent each other when the binder is opened so as to permit the other cover and said flexible section being folded back against said one cover to hold the latter in extended substantially coplanar relation with the other panel of said pair of panels when the easel is extended into supporting relation, the connecting section of said covers enclosing said mechanical binding when the binder is closed. 20
5. A display device comprising a plurality of sheets having mechanical binding, a pair of rigid cover members, a section connecting adjacent edges of said cover members, one of said cover members having a part receiving said mechanical binding, and a supporting easel interfitting with said mechanical binding and connected with the other of said cover members. 25
6. A display device comprising a plurality of wire-bound sheets, a pair of rigid cover members, a section connecting adjacent edges of said cover members, one of said cover members having a part receiving the wire binding said sheets, a sup- 30
- porting easel including a rigid panel, a second panel, both also bound in with said wire bound sheets, and a folding section connecting said panels, and means fixing said second panel to the other of said cover members. 5
7. A display binder comprising a pair of interconnected rigid members, loose-leaf metal carried by one of said members, and easel means interfitted with said loose leaf metal and both of said members for supporting the latter in generally upright position for display purposes. 10
8. A display binder comprising a pair of flexibly interconnected rigid cover members, binding means carried by one of said members and including sheet receiving arches having straight sides, and a folding easel interfitting with said arches and connected with the other of said members. 15
9. A display binder comprising a pair of hingedly interconnected rigid members, one comprising a cover for the binder, a ring binder carried by one of said rigid members and adapted to support a plurality of sheets thereon, and means interfitting with said ring binder and connected with said rigid members to support the latter in generally upright position. 20
10. A display device comprising a plurality of sheets perforated along one edge, binding means including ring-like sections extending through the perforations of said sheets and a connecting joint to which said sections are secured, a pair of panels perforated to correspond to the perforations of said sheets and receiving said ring-like sections with said joint concealed therebetween, and means interfitting with said binding means for holding said pair of panels in generally upright position, the disposition of said binding means joint providing for the free movement of said sheets from one side to the other of said ring-like sections. 30
11. A display device comprising a plurality of sheets having mechanical binding means, a pair of rigid cover members, a section connecting adjacent edges of said cover members, one of said cover members having a part receiving said mechanical binding, a supporting easel comprising means serving as a pair of panels interconnected by a hinged fold line and apertured adjacent said fold line to receive said binding means, the opposite edge of one of said panels being secured to the other cover and the other panel being rigid, and means to limit the outward movement of said rigid panel. 35
12. A display device comprising a pair of rigid covers, a section connecting and disposed between said covers, sheet binding means connected with one of said covers, an easel panel interfitting with said binding means and having parts folded back to impart rigidity to the panel, and tension members interfitting with said binding means and connecting the other cover thereto and to said rigid panel. 40
13. A display binder comprising a pair of rigid cover members, a section connecting adjacent edges of the cover members, a plurality of sheets having perforations along one edge, binding means of a mechanical nature carried by one of said cover members and having ring-like sections extending through the perforations in said sheets and permitting the latter to be turned over progressively from one side of the binder to the other when the binder is opened, a foldable easel normally folded between said sheets and the other cover member and comprising three panels adapted when extended to form a triangle, one 45

panel connecting the other two panels at points spaced from their inner edges and said other two panels being perforated adjacent their inner edges and receiving said binding means, and
5 means connecting the outer of said two panels to said other cover member at a point spaced from said section, the effective length of said outer panel being such that when said easel is extended and said one cover member is swung
10 backwardly so that it bears at a point spaced from its inner edge a distance substantially equal to the width of said flexible section against the inner edge of the other cover member, said outer easel panel acts in tension to hold said one cover
15 member and the inner of said two easel panels in substantially coplanar relation, thereby providing for the simultaneous display of two sheets to present a double page spread.

14. A display binder comprising a pair of rigid
20 cover members, a section connecting adjacent edges of the cover members, a plurality of sheets having perforations along one edge, one of said cover members having a perforated section, the perforations of which correspond to the perforations in said sheets, mechanical binding having generally arcuate parts extending through the perforations in said sheets and said cover section whereby said mechanical binding is carried by said one cover member and said sheets are
25 adapted to be turned over progressively from one side of the binder to the other when the binder is opened, a foldable easel normally folded between said sheets and the other cover member when the binder is closed and comprising three
30 panels adapted when extended to form a triangle, one panel being constructed so as to tend to fold inwardly and when extended to connect the other two panels at points adjacent their outer edges, the inner edges of said two panels being perforated to receive said binding means,
35 either or both of said one cover member and said two panels moving on said binding means toward each other when said one cover member is swung backwardly about said section so as to bear against the inner edge of the other cover member, and means connecting the outer edge of said outer panel to the outer edge of said other cover section, whereby said outer easel panel acts in tension to hold said one cover member and the
40 inner of said two easel panels in substantially coplanar relation, thereby providing for the simultaneous display of two sheets to present a double page spread.

15. A display binder comprising a pair of rigid
55 cover members, a section connecting adjacent edges of the cover members, a plurality of sheets having perforations along one edge, loose leaf metal secured rigidly to one of said cover members adjacent its inner edge and having arch
60 members extending through the perforations in said sheets and permitting the latter to be turned over progressively from one side of the binder to the other when the binder is opened, a foldable easel normally folded between said sheets and the other cover member when the binder is closed and

comprising three panels adapted when extended to form a triangle, one panel being constructed so as to tend normally to fold inwardly and connecting the other two panels adjacent their outer edges, said other two panels being perforated adjacent their inner edges to receive the binding means of said loose leaf metal and movable relative thereto from one side of the loose leaf metal to the other side thereof adjacent the inner edge of said one cover member when the latter is swung backwardly about said section so as to bear against the inner edge of said other cover member, and means securing the outer edge of the outer of said two panels to the outer edge of said other cover member whereby said outer easel panel acts in tension to hold said one cover member and the inner of said two easel panels in substantially coplanar relation, thereby providing for the simultaneous display of two sheets to present a double page spread.

16. A display binder comprising, in combination, substantially rigid front and back covers, a section interconnecting adjacent edges of said covers, a substantially rigid panel hingedly connected at its inner edge to one of said covers along said adjacent edge thereof, a flexible connector interconnecting the other of said covers and said rigid panel for limiting movement apart thereof through a predetermined angle, and means for limiting movement apart of said one cover and said panel through a predetermined angle.

17. A display binder comprising, in combination, substantially rigid front and back covers, a section interconnecting adjacent edges of said covers in spaced apart relation sufficiently to permit said covers to lie substantially parallel to each other when the binder is filled and closed, a substantially rigid panel hingedly connected at its inner edge to one of said covers along said adjacent edge thereof, a connector interconnecting the other of said covers and said rigid panel for limiting movement apart thereof through a predetermined angle, and means for limiting movement apart of said one cover and said panel through a predetermined angle.

18. A display binder comprising, in combination, substantially rigid front and back covers, a section interconnecting adjacent edges of said covers in spaced apart relation sufficiently to permit said covers to lie substantially parallel to each other when the binder is filled and closed, a substantially rigid panel hingedly connected at its inner edge to one of said covers along said adjacent edge thereof, means including a plurality of hingedly connected members hingedly connected to the other of said covers and said rigid panel for limiting movement apart thereof through a predetermined angle and adapted to be folded therebetween when the binder is closed, and means for limiting movement apart of said one cover and said panel so that one forms substantially an extension of the other when the binder is open.

ELMER W. ERICSON.

CERTIFICATE OF CORRECTION.

Patent No. 2,208,213.

July 16, 1940.

ELMER W. ERICSON.

It is hereby certified that error appears in the printed specification of the above numbered patent requiring correction as follows: Page 5, second column, line 9, claim 7, before the word "both" insert --connected with--; and that the said Letters Patent should be read with this correction therein that the same may conform to the record of the case in the Patent Office.

Signed and sealed this 27th day of August, A. D. 1940.

Henry Van Arsdale,

(Seal)

Acting Commissioner of Patents.
